UNITED STATES PATENT OFFICE.

HARRY JONES, OF SUFFERN, NEW YORK, ASSIGNOR TO THE AMERICAN BRAKE SHOE & FOUNDRY COMPANY, OF WILMINGTON, DELAWARE, A CORPORATION OF DELAWARE.

MOLDING BRAKE-SHOE INSERTS.

1,375,702.

Specification of Letters Patent. Patented Apr. 26, 1921.

Application filed July 24, 1920. Serial No. 398,692.

To all whom it may concern:

Be it known that I, HARRY JONES, a citizen of the United States, residing at Suffern, in the county of Rockland and State of New York, have invented certain new and useful Improvements in Molding Brake-Shoe Inserts, of which the following is a specification.

This invention relates to the manufacture 10 of brake shoe inserts of that type which comprises a plurality of blocks or sections cast at intervals on supporting strips of reticulated metal, such as expanded metal or wire mesh.

15 The object of this invention is to make it possible to produce brake shoe inserts of the kind above described in green sand molds, and thereby avoid the necessity of providing numerous cores which would be 20 required in ordinary foundry practice and seriously retard production and increase the cost.

25 A further object of the invention is to simplify and improve the preparation of the mold for making the insert by the provision of means for blowing out any sand that may have entered the mold cavities without injuring the surface of the mold, and also facilitating the removal of the 30 patterns from the mold without injury to the mold.

In ordinary foundry practice it does not appear to be practicable to make a mold 35 wherein strips of reticulated metal are placed in a longitudinal position, passing alternately through the sand portion of the mold and through a series of mold cavities, each cavity of the series forming a separate casting when metal is poured therein, 40 it being required that said strips be held firmly in position during the process of molding and that the several cast portions of insert form a solid cast body through and about the connecting metal strips in the 45 process of casting.

In the manufacture, by ordinary foundry practice, of the limited numbers of these inserts necessary to test their efficiency it was found necessary to construct a core box in 50 which strips of expanded metal were arranged. Core sand was then rammed into the core box and the core was turned out on a plate and baked, after which the core sand was picked out from among the expanded 55 metal strips in sections of the core where

cast portions of insert were required. This core was then placed in a green sand mold wherein gate runners were cut, connecting each of the individual molds to a main runner or gate, so that each of the molds was 60 filled from one pouring gate.

My invention provides a series of patterns of necessary shape and dimensions for forming each of the cast sections of the insert; 65 said patterns are properly placed on a pattern plate and projected through suitable openings in a stripping plate. For such arrangement, I claim no invention. However, I do claim invention in the provision of suitable slots or recesses in these patterns, 70 so arranged as to permit dropping of continuous longitudinal strips of reticulated metal into position required in the construction of the insert, said strips resting firmly 75 on the stripping plate and being held firmly in position as to lateral emplacement during the processes of ramming sand into the mold and drawing the patterns through the stripping plate preparatory to lifting the 80 mold therefrom.

I claim further invention in the means of applying jets of air to each of the mold cavities for the purpose of removing such molding sand as may find its way into slots or recesses in the patterns and remain clinging to the strips of reticulated metal, where they pass through the mold cavities, after 85 patterns are withdrawn, such air jets being applied before the mold is lifted from the stripping plate so that the surface of the 90 mold is not broken or disturbed by its application.

It is further a matter of great convenience to have these series of insert patterns fitted 95 with air jets that are operated simultaneously.

In the accompanying drawings illustrating a selected embodiment of the invention

Figure 1 is a perspective view of a machine for making two inserts, showing the 100 flask and stripping plate partly broken away and with expanded metal strips arranged in one set of patterns;

Fig. 2 is a perspective view of the drag part of the flask ready to receive the cope; 105 and

Fig. 3 is a perspective view of one of the patterns for forming the mold cavity for the insert blocks or sections.

Referring to the drawings, 4 is a verti- 110

cally movable support suitably guided in the frame 5 of the machine and adapted to be operated by a shaft 6 connected with the support in any suitable manner. A pattern 5 plate 7 is mounted on the support and guided in the frame and this plate carries a plurality of patterns 8 each of which consists of a block provided in its upper portion with a plurality of parallel slots 9 10 spaced apart a predetermined distance to receive the strips 10. A stripping plate 11 is mounted on the frame and is provided with a plurality of openings 12 through which the upper slotted portions of the 15 patterns project and the construction is such that in operative position the bottom of the slots will lie in substantially the plane of the top of the stripping plate. The strips 10 are supported in parallel position in the 20 slots of the patterns and rest upon the bottom of the slots and upon the stripping plate. Each of the patterns is provided with an air chamber 13 from which passages 14 lead to the bottom of the slots 9 25 and a pipe 15 is mounted on the pattern plate and is suitably connected by branches with each of the patterns. A hose 16 is connected to the pipe 15 and to a source of air supply (not shown).

30 In practice the standard is adjusted to raise the pattern plate and project the patterns up through the stripping plate, as shown in Fig. 1. The expanded metal strips or other reticulated metal strips are 35 arranged side by side in the slots of the patterns resting on edge upon the patterns and upon the stripping plate. Then the flask 17 is placed on the stripping plate and sand is rammed up therein around the 40 patterns and strips in the usual manner for making a mold. The shaft 6 is then operated by turning the crank 6' to lower the pattern plate and withdraw the patterns from the sand and clear of the top surface 45 of the pattern plate, leaving mold cavities in which the metal is to be poured to cast the blocks or sections upon the strips and form the insert for the brake shoes. It often happens that these mold cavities contain 50 more or less loose sand clinging to the strips or otherwise disposed therein and, as before stated, it has been customary heretofore to remove the flask from the machine and blow this sand out of the mold cavities 55 by the use of a hand bellows. This blowing out operation must be separately performed on each mold cavity and it frequently results in injury to the surface of the mold which necessitates repairing the mold or 60 making it over again. My invention greatly simplifies this blowing out operation and avoids the danger of injuring the mold by conducting the blowing out operation on all of the cavities simultaneously and before 65 the flask is removed from the stripping

plate. When the patterns have been withdrawn, as heretofore described, air is admitted to the pipe 15 and flows through the chambers 13 and the passages 14 up through the slots 9 and into the mold cavities, 70 blowing out the loose sand in the mold cavities before the mold has been removed from the machine. The air blast is introduced into all of the mold cavities simultaneously and under uniform pressure before the mold 75 has been removed from the machine and the danger of injuring the mold surface is thereby reduced to a minimum if not entirely eliminated. The strips are firmly supported on the stripping plate when the 80 patterns are withdrawn from the mold so that this operation can be performed without agitating or disturbing the strips and without breaking up the sand forming the mold.

85 In the drawings I have shown one embodiment of the invention which may be satisfactorily employed but it will be understood that the shape of the patterns may be changed, if desired, and that other changes 90 in the form, construction and arrangement of parts may be made within the scope of the following claims. And while expanded metal is a form of reticulated metal which I regard as especially desirable for the connecting strips, it will be understood that I use the word "reticulated" in a broad sense to include not only expanded metal and wire mesh but also any other kind of metal strip of a reticulated or a foraminous 95 construction.

100 I claim:

1. In a machine for molding brake shoe inserts comprising a plurality of blocks or sections cast at intervals on supporting and connecting strips, the combination of a mold support, a plurality of movable patterns to form cavities in the mold in which the blocks or sections are cast, said patterns being slotted to receive and support the strips upon which said blocks or sections are cast, and means for moving the patterns into and withdrawing them from the mold.

115 2. In a machine for molding brake shoe inserts comprising a plurality of blocks or sections cast at intervals on supporting and connecting strips, the combination of a mold support having openings therein, a plurality of patterns movable through said openings into and out of the mold to form 120 cavities in the mold in which the blocks or sections are cast, said patterns tapering from the lower portions to the top thereof to facilitate withdrawal from the sand and being slotted transversely between their 125 ends to receive and support the strips upon which said blocks or sections are cast, and means for moving the patterns into and withdrawing them from the mold.

130 3. In a machine for molding brake shoe

- inserts comprising a plurality of blocks or sections cast at intervals on supporting and connecting strips, the combination of a mold support, a plurality of movable patterns to 5 form cavities in the mold in which blocks or sections are cast, said patterns being arranged side by side in parallel relation and being slotted transversely in their upper portions and between their ends, the slots in 10 the several patterns being located in alignment to receive and support the strips upon which said blocks or sections are cast, and means for moving the patterns into and withdrawing them from the mold.
- 15 4. In a machine for molding brake shoe inserts comprising a plurality of blocks or sections cast at intervals on supporting or connecting strips, the combination of a mold support, a plurality of movable patterns to 20 form cavities in the mold in which the blocks or sections are cast, said patterns being slotted to receive and support the strips upon which said blocks or sections are cast, means for supplying an air blast 25 through the patterns to the slots therein, and means for moving the patterns into and withdrawing them from the mold.
5. In a machine for molding brake shoe inserts comprising a plurality of blocks or 30 sections cast at intervals on supporting or connecting strips, the combination of a mold support, a plurality of movable patterns to form cavities in the mold in which the blocks or sections are cast, said patterns 35 being slotted to receive and support the strips upon which such blocks and sections are cast, air passages in the patterns and connections thereto to supply an air blast through the patterns to said cavities, after 40 the patterns have been withdrawn from the mold, to clean said cavities preparatory to the casting operation, and means for moving the patterns into and withdrawing them from the mold.
- 45 6. In a machine of the character described, the combination of a mold support, a pattern for the mold, means for withdrawing the pattern from the mold, and means for supplying an air blast through the pattern 50 to the mold cavity.
7. In a machine of the character described, the combination of a mold support having a plurality of openings, a pattern plate, a plurality of patterns mounted on the plate 55 and adapted to operate in said openings, means for withdrawing the patterns through said openings from the mold, and means for supplying an air blast simultaneously through each pattern to the mold cavities.
- 60 8. In a machine of the character described, the combination of a mold support having a plurality of openings, a plurality of patterns operating in said openings and each having a plurality of parallel slots, means for withdrawing the patterns from the mold, 65 and means for supplying an air blast through the slots in the patterns simultaneously to all of the mold cavities.
9. In a machine of the character described, the combination of a mold support having 70 a plurality of openings, a plurality of patterns operating in said openings, means for withdrawing the patterns from the mold, each of said patterns having a plurality of slots therein, an air chamber, passages leading from said chamber to said slots, and means for supplying air pressure to said chambers.
10. In a machine of the character described, the combination of a stripping plate 80 having a plurality of openings therein, a plurality of patterns operating in said openings, means for withdrawing the patterns from the mold, each of said molds having means for conveying air pressure there- 85 through to the mold cavities, and a pipe connected to all of said molds and to a source of air supply to admit pressure to all the patterns simultaneously.
11. In a machine of the character de- 90 scribed, the combination of a stripping plate having a plurality of openings therein, a plurality of patterns operating in said openings, means for withdrawing the patterns from the mold, each of said patterns comprising a block having a plurality of slots in its upper portion spaced apart, an air chamber in its lower portion, an air passage leading from said chamber to the bottom of said slots, and means for supplying air pressure 95 to said patterns and through them to the mold cavities when the patterns are withdrawn from the mold.
12. The herein described improvement in the art of making molds for brake shoe inserts which consists in providing a plurality of movable patterns for the insert blocks or sections projecting upward through openings in the mold support of a mold flask, each of said patterns being slotted to support strips of reticulated metal in parallel relation, ramming sand in the flask around the patterns and the strips, withdrawing the patterns from the mold downward through the support, and admitting a blast of air 105 through the patterns to the mold before removing it from the machine to blow out any loose sand which may remain in the mold cavities and from those portions of the strips in said cavities.

HARRY JONES.
